(Cl. D61—1)

To all whom it may concern:

Be it known that we, Jack Briskin and Conrad Peto, respectively, citizens of the United States, residing at Chicago, in the county of Cook and State of Illinois, have invented a new, original, and ornamental Design for a Movie Projector, of which the following is a specification, reference being had to the accompanying drawings, forming a part thereof, in which,

Fig. 1 is a view of one side of a movie projector showing our new design;

Fig. 2 is a top view thereof;

Fig. 3 is a front view thereof;

Fig. 4 is a view of the other side thereof; and

Fig. 5 is a rear view thereof.

We claim:

The ornamental design for a movie projector, as shown.

JACK BRISKIN.
CONRAD PETO.
